UNITED STATES PATENT OFFICE

GEORGE H. MYERS, OF BRIDGEPORT, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed June 2, 1928. Serial No. 282,303.

The present invention relates generally to ribbon-feeding mechanism of typewriting machines, and more particularly to means for automatically reversing the ribbon-feed of a portable typewriting machine.

It is a feature of the invention to provide light, compact ribbon-feed-reversing mechanism, which is set in operating condition by a predetermined controlling movement of the ribbon, and which is operated thereafter by power from the depression of a key and momentum of the associated type-bar that neither the controlling operation nor the final operation requires enough additional force to appreciably increase the usual resistance of the keys to the touch.

In carrying out my invention in an Underwood portable typewriter, the keys are operatively connected to the usual ribbon-feed-reversing mechanism when the ribbon reaches a predetermined point. A pivoted carrier-member associated with each spool is operatively connected to a usual oscillating lever, which operates a drive-pawl for rotating a coaxial ratchet-wheel fastened to the spool.

A normally-ineffective actuator-lever is pivoted on each oscillating carrier, and the lever associated with the feeding spool is movable to a position by the ribbon, wherein it is effective upon the next oscillation of the carrier to rotate a cam, which will connect the associated ratchet-wheel and its released pawl. The lever is moved to effective position by a lever-system which is operated by the ribbon when the latter has been substantially unwound from the feeding spool. The next depression of a key reverses the ribbon-feed mechanism, because the two pawl-controlling cams are connected as usual, so that when the pawls of one spool are made effective for rotating the spool ahead, the pawls of the other spool are disabled to permit that spool to be reversely rotated for unwinding the ribbon therefrom.

It is another feature of the invention to assemble, as a unit, the ribbon-control mechanism and the key-operated mechanism for each spool on a single bracket which is easily mounted on the usual shift-frame.

It is still another feature of the inven-

tion to provide a detent-device on one of the pawl-disconnecting cams, which device is also effective to help considerably in moving the cams to the end of their travel in either direction. This detent-device replaces the usual detent-device heretofore used with the manually-operated feed-reversing mechanism.

Other features and advantages will hereinafter appear.

In the accompanying drawings,

Figure 1 is a fragmentary sectional view, front to rear, of an Underwood portable typewriting machine, having my invention applied thereto.

Figure 2 is a fragmentary cross-section through the mechanism associated on the right-hand ribbon-spool, the cross-section being taken at a substantial right angle to the plane of the section in Figure 1, and certain parts being shown in elevation.

Figure 3 is a fragmentary perspective view of a unitary mechanism of the invention for controlling the reversing of the ribbon-feed mechanism by movement of the ribbon.

Figure 4 is a fragmentary plan view of the ribbon-spools of the present invention, and certain associated parts which illustrate how the ribbon-feeding mechanism of one spool operates reversely from the other spool. In this view the left-hand spool is disposed for winding up the ribbon, and the other spool is feeding out the ribbon.

Figure 5 is a fragmentary perspective view of the right-hand ribbon-spool and the associated mechanism of the present invention for automatically reversing the ribbon-feed. In this view the ribbon is shown substantially unwound from the spool, and a button on the ribbon is about to engage the reversing mechanism.

Figure 6 is a view similar to Figure 5, the ribbon having moved a trip-lever and an actuator-setting mechanism to effective position for operating the reversing cam at the next depression of the typewriter-key.

Figure 7 is a view similar to Figure 5, the actuator, which is operatively connected to the universal bar, being shown in operated position wherein it has moved the reversing

cam-plate clear of the drive-pawl, the latter being now in operative engagement with the ratchet-wheel of the ribbon.

The present invention is illustrated in connection with an Underwood portable type-writing machine in which keys 10 are fastened on key-levers 11, each of which is pivoted on a lateral rod 12, fast to a main frame 13. Each lever 11 is operatively connected 10 to a type-bar 14 by interponents including a bell-crank 15 having a forward slotted arm 16 arranged for engagement with a pin 17 in the lever 11, and a rear arm 18 connected by a link 19 to a lower arm-member 20 of the 15 type-bar 14. Each type-bar is pivotally mounted on a curved rod 21, fast on a segment not shown, and depression of its corresponding key 10 causes it to be swung rearwardly against a platen 22 mounted on a shaft 23 20 journaled in a carriage 24. A spring 25 returns each lever 11, and its associated type-bar 14, to normal position after each type-stroke. The parts described hereinbefore may be of usual construction.

25 Upon depression of a key 10 the platen-carriage is letter-spaced from right to left by usual instrumentalities, not shown, and the lever 11 associated with the key is swung downwardly against a universal bar 26, which 30 is disposed a short distance below the lever and is mounted for oscillation on a rock-shaft 27. The lever is normally urged upward against a stop-pin 29 by a contractile spring 28.

35 Interponents, not shown, operatively connect the universal bar 26 to a ribbon-vibrator 30, through which a ribbon 31 is threaded in the usual way, the vibrator being vibrated upwardly in front of the printing point just 40 before a type 32 on a type-bar 14 strikes the platen. The construction of the universal bar 26, the vibrator 30 and the interponents connecting the latter to the bar may be the same as disclosed in the co-pending application of 45 William A. Dobson, No. 67,297, filed November 6, 1925 (now Patent No. 1,715,906, dated June 11, 1929).

It is usual in typewriter construction to have the ribbon 31 reeled on two spools 40, 50 rotatably mounted on different sides of the printing point for winding the ribbon alternately from one spool to the other through the vibrator, a small amount at each type-stroke. In the present invention each spool is journaled on the upper portion of a vertical spindle 41, the lower portion of which is journaled in a vertical bushing-member 42, and is held therein by a screw 43 in the lower end of the spindle. Thumb-nuts 44 hold the 55 spool in place on the spindle 41. The bushing 42 is rotatably mounted on a bracket 45, which may have the form of a short section of rectangular tubing, which may be fastened by screws 46 to an adjacent side plate 47 of the usual shift-frame. A cam-plate,

generally designated as 48, is fastened to the upper end of each bushing 42 for a purpose to appear hereinafter. Between the cam-plate and the top of the bracket 45 is disposed a thin in-reaching arm 49 which is pivoted about the bushing 42 for a purpose to presently appear.

70 A usual ratchet-wheel 50 is loosely mounted on each spindle 41 between the cam-plate 48 and the ribbon-spool 40, being spaced away from the spool and the cam-plate by usual hubs. A usual up-reaching pin, not shown, on each ratchet-wheel releasably engages in a hole, not shown, in the associated ribbon-spool, and operatively fastens the latter to 75 its ratchet-wheel.

75 To the end that a small amount of ribbon 31 may be wound on either of the spools 40, and off the other, each time a character is typed, two up-reaching arms 51 are fastened 80 on the rock-shaft 27, one arm being disposed adjacent each side plate 47. A forwardly and upwardly extending link 52 connects the upper end of each arm 51 to the lower end of an upright lever 53, which is pivoted about a 85 screw 54 threaded in the inwardly-disposed wall of the adjacent bracket 45. A short portion of the upper end of each lever 53 is bent inwardly to form a wrist-member 55, which has an open slot 56 for engaging about 90 a depending pin 57 fastened to the arm 49.

95 A drive-pawl 60 is pivotally mounted on the outer end of each arm 49, and has an up-reaching tooth 61 for engagement with the adjacent ratchet-wheel toward which it is urged by a contractile spring 62, which has one end fastened to a depending lug 63 on the pawl 60, and the other end to a depending lug 64 on the arm 49.

100 As will appear hereinafter, one of the drive-paws 60 is always disposed in effective position, and the other pawl is always in ineffective position. The depression of any key 10 will be effective to oscillate each of the pawls 60 on the arms 49, and will therefore 105 rotate step by step the ratchet-wheel 50 associated with the effectively-disposed pawl. The construction of the drive-paws may be substantially the same as is set forth in the patent to Lee S. Burridge, No. 1,249,022, 110 dated December 4, 1917.

115 To prevent reverse movement of a ratchet-wheel 50 while being driven ahead by its drive-pawl 60, a dog-pawl 65 is pivoted on an in-reaching bracket-arm 66 on the adjacent shift-frame side plate 47, and is urged toward the ratchet-wheel by a contractile spring 67, which has one end fastened to a depending lug 68 on the dog-pawl and the other end fastened to the adjacent side plate.

120 The ratchet-wheel 50 and the pawls 60 and 65 are oppositely disposed, and it is necessary to hold the pawls of one spool in ineffective positions while the ribbon is being unwound from the spool associated with the in- 125

effective pawls. To this end, each cam-plate 48 has two radial arm-members 70 and 71 arranged with cam-edges 72 effective upon rotation of the cam-plate for camming the pawls 60 and 65, respectively, away from the ratchet-wheel associated with the screw from which the ribbon is being wound. The principle of operation of the cam-plate is more fully explained in the above-noted patent to Burridge.

To arrange for one set of pawls 60 and 65 to be moved by spring-action to effective positions simultaneously as the other set of pawls is cammed to ineffective positions, a 15 forwardly-extending arm 73 may be fastened securely, as by clamping, to the lower end of each bushing 42 which protrudes below the bracket 45, and the forward ends of the arms are operatively connected by a substantially 20 U-shaped connecting link 74 of stiff wire. The upper end-portion of each upright member of the U-shaped link is bent at a right angle rearwardly and then downwardly. Each downwardly-bent end portion 75 of the link engages loosely in a vertical hole in the forward end of the adjacent arm 73. This construction permits a horizontal base-portion 76 of the link 74 to be disposed beneath the forward ends of the type-bar 14.

To the end that the feed of the ribbon 31 may be manually reversed at will, an upwardly-extending lever 77 is pivoted on a screw 78 against the inner face of a front plate 80 and adjacent the right side of the 25 machine. The lever is bent forwardly at 81 for passing through a slot 82 in the front plate, and is bent upwardly again at 83 to have its upper portion compactly disposed against the forward face of the front plate, 30 the lever terminating in a ball 84. An arm 85 is fastened rigidly to the lever 77 between its pivot and the slot 82, and extends rearwardly and terminates in two integral forks 86, which engage on either side of the right- 45 hand upright member of the U-shaped link 74. As illustrated in Figure 4, the lever 77 is thrown to the right and the pawls of the right-hand spool 40 are disposed in ineffective positions. For a reason to appear hereinafter, 50 the lever 77 is preferably mounted to move freely about its pivot, and engages no deterrent device, as employed heretofore, for holding it in its rightmost or leftmost position.

To the end that the feed of the ribbon 31 from either ribbon-spool to the other may be 55 quickly and automatically reversed when substantially all the ribbon has been unwound from one of the spools 40, two buttons or rivets 90 are fastened to the ribbon for co-operation with novel mechanism of the invention for reversing the feed of the ribbon-spools. The reversing mechanism, except as herein-after noted, will be described for only the right-hand spool, it being understood that a 60 similar mechanism is provided for the other

spool. One button 90 is positioned adjacent each end of the ribbon a distance adjacent therefrom that preferably will leave approximately one turn of the ribbon wound around a usual core 91 of the adjacent spool when 70 the button moving with the ribbon, towards the vibrator 30, has passed through a slot 92 of the usual ribbon-spool cup 93 and engaged against the upper end of a lever 94, herein-after called a trip-lever.

This lever has its lower end pivoted on a rivet 94 in a bracket-arm 95 of the main bracket, generally designated as 96, which may be fastened by a plurality of screws 97 to the adjacent side plate 47. It will be noted (Figures 4 and 6) that the lower end portion of the trip-lever 94 has an integral flange-member 98, which is bent transversely to the plane of the trip-lever. The face of this flange is disposed against a face of an outer end portion 99 of the bracket-arm 95, which is bent to be directed substantially at the ribbon-vibrator 30. By this advantageous construction, the ribbon 31, which is fed from the core 91, to the vibrator 30, in a plane substantially tangent to the core (Figure 4), remains substantially straight, while the button 90, which it carries, operates the trip-lever 94. The force required to operate the trip-lever is thereby reduced, and the strain on the ribbon lessened. In the ineffective position of the trip-lever, as illustrated in Figure 5, its upper end is disposed compactly against the ribbon-spool cup, and a lengthwise slot 100 in the trip-lever registers with the slot 92 in the cup 93.

It is a feature of the present invention to reverse the ribbon-feed by power created by the depression of a key 10 by immediately following the movement of the trip-lever 94 to effective position. For transmitting this power to the hereinabove-described means employed for moving the reversing cam-plates 48, use is made of the lever 53, which is oscillated at each operation of a key 10. An elongated lengthwise slot 101 is provided in the lever 53 a short distance below its pivot-screw 54. A laterally-disposed pin 102 has one end positioned for engaging loosely in the slot 101, and extends therefrom to the right to be fastened rigidly in a part generally designated as 103, and herein-after called an actuator-carrier. The carrier may be made from thin sheet-metal and have a plane body-portion 104, whose side elevation, as shown in Figure 1, may have the approximate form of a rectangle with a triangular section cut out of its upper left-hand corner.

The carrier 103 is pivoted for oscillation in a vertical plane parallel to the lever 53 on a shoulder-screw 105, threaded into the right side of a forward extension 106 of an in-reaching bracket-arm 107, disposed above the bracket-arm 95 and integrally joined to the main bracket 96. A rearwardly-extend-

ing stop-finger 108 is integrally joined to the body 104 at its rear lower corner, and has a leftward extension 110, which passes below the bracket-arm extension 106. This 5 construction prevents the actuator-carrier from being swung too far clockwise about the pivot-screw 105 by its own weight, the center of gravity of the carrier being disposed in front of a vertical plane through 10 its pivot, as will be seen from an inspection of Figure 1.

The pin 102 is fastened in the carrier-body portion 104 a short distance below its pivot-screw 105 (Figures 1 and 3). Therefore, 15 each time the lever 53 is swung forward by depression of a key 10, the actuator-carrier 103 is rocked counterclockwise about its pivot-screw. An actuator-member in the form of a thrust-lever 111, for moving the reversing cam-plate 48, is pivotally mounted on a screw 112 in a rightwardly-extending integral flange-member 113 of the body-portion 104, and extends upwardly toward the cam-plate. The lever 111 is urged leftwardly by a contractile spring 114, which has one end fastened to a forwardly-bent integral lug 115 on the lever, and the other end to an integral lug 116 on the body 104. An integral strap-like lug 117 on the body 104 20 is positioned above the screw 112 and extends forward as far as the front face of the thrust-lever, and is bent to the right to extend along in front of the lever for a purpose to presently appear. The lug 117 also 25 serves to arrest the lever 111 in its leftmost position when moved thereto by the spring 114. To stop the lever 111 in its rightmost position, there is provided an integral depending hook-member 118 on the lever 111, which is arranged to engage against the left 30 side of the lug 117 when the lever 111 has been moved to its rightmost position by means to be described hereinafter.

To provide an operative connection between the cam-plate 48 and the thrust-lever 111 the cam-arm 70 has an integral abutment lug 119 depending from its inner edge. The lug 119 terminates preferably one-fourth inch or more below the top of the lever 111, and is disposed to the right side of the normal path of the upper end of the lever 111, when the latter is swung to the rear at ordinary type-strokes. The lug 119 in its forward position is spaced a short distance to 35 the rear of the lever 111.

To permit the lug 119 to pass the underlying pawl-carrying arm 49, a circumferential slot 120 is cut in the arm, which permits vibratory movement of the latter, for rotating the ratchet-wheel 50, without interference by the lug 119, and also permits rotary movement of the cam-plate 48 independently of the oscillating arm 49. The length of the circular arc of the slot 120 exceeds the angular movement of the cam-plate 48 plus

that of the arm 49, since at certain times the cam-plate 48 may be moving in the opposite direction to the arm 49.

To make the movement of the lever 94 by the button 90 effective for moving the actuator-lever 111 into position for engaging the depending lug 119, a Z-shaped transfer lever 121 is pivoted about a screw 122 in an upwardly-spaced, rightwardly-extending, integral flange 123 of the bracket-arm extension 106. An arm 124 of the lever 121 extends rearwardly adjacent the right side of the lever 94, and has a depending member 125. Since the last-named lever is swung to the left by movement of the ribbon 31, an integral U-shaped hook 126 is provided on the lever 94 and extends in a substantially horizontal plane to the rear, past the member 125, then to the right past said member, and then forward past said member again (Figure 3).

Another arm 127 of the lever 121 extends forward slightly past the lever 111, and is normally disposed adjacent the left side of its upper end portion (Figure 2). When most of the ribbon 31 is unwound from the right-hand spool 40 the button 90 will move up against the lever 94, and at each type-stroke thereafter will swing it to the left away from the cup. The arm 127 of the transfer lever 121 is swung to the right and carries with it the lever 111 which is being oscillated toward the rear at each type-stroke. The upper end of the lever 111 is thus moved over to the right until its path to the rear will intersect the lug 119. Thereupon the next operation of a key 10 causes the lever 111 to engage the lug 119 and thrust it rearwardly, and swing the arms 70 and 71 clockwise out of engagement with pawls 60 and 65, respectively, and their respective return springs will swing them into engagement with the right-hand ratchet-wheel 50.

As will be understood from the above explanation of the operative connection between the cam-plates 48 of the right-hand and left-hand ribbon-spools, the pawls of the left-hand spool will be disabled, i. e., made ineffective concomitantly with the releasing of the pawls of the right-hand spool for effective engagement with their associated ratchet-wheel.

A detent-device generally designated as 130 is provided for holding the cam-plate 48 securely in its effective pawl-releasing position or in its ineffective position clear of the pawls. This device includes a short extension 131 of the plate on the opposite side of its axis from the arms 70 and 71. The outer end of the extension 131 is provided with two triangular V-shaped notches 132. A ball 133 disposed in a hole 134 in the right-hand side plate 47 and pressed by a leaf-spring 135 fastened on the outer face of the side plate, is arranged to engage in the forward notch 132 when the cam-edges engage the pawls (Figure 6), or in

the rear notch when the cams are clear of the pawl (Figure 7.)

The engagement of the ball in the notches will yieldingly hold the cam-plate from creeping out of either its effective or ineffective position, but will not prevent the rotary movement of the cam-plate by the above-described reversing mechanism. It can also be seen by those skilled in the art that the co-operation of the spring-pressed ball and the notches provides a further advantage by helping in a wellknown way to move the cam-plate in either direction to the end of its travel after the tooth between the notches passes the center of the ball. It will be noted that the detent-device 130 on the right-hand cam-plate also controls the left-hand cam-plate through the above-described operative connection between the cam-plates.

20 The right-hand spool 40, having been made effective for winding up the ribbon 31, the button 90 will then move toward the core 91 of the right-hand spool at each type-stroke, and the trip-lever 94 is caused to follow the button closely by a contractile spring 137, which has one end fastened to a rightwardly-bent integral lug 138 on the lever 94 (Figure 3), and the other end fastened to a lug 139, which is integrally joined to the top edge of the bracket-arm 107 adjacent the left end thereof and extends therefrom to the right, being bent forward enough to bring the line for force of the spring 137 nearly parallel to the line of movement of the trip-lever 94. 35 This prevents binding of the lever 94 about its pivot, and makes for easier operation of the lever and the actuator-controlling mechanism.

It will be seen upon inspection of Figure 1 that a key-lever 11 does not strike the universal bar 26 at the beginning of the down stroke, and therefore does not instantly begin to move the mechanism provided for operating the cams 48.

45 It will be further noted that the top of the lever 111 is normally spaced a short distance forward from the lug 119. Thus, when the lever 111 engages the lug, the type-bar 14 associated with the depressed key 10 will have already moved over a large part of its travel toward the printing point, and will have acquired considerable momentum, which will be effective through its connection to the lever 53 to help rotate the cam-plate 48, and thereby decrease the amount of the additional force required for depressing the key 10, which has to both type the letter and reverse the ribbon-feed.

50 Variations may be resorted to within the scope of the invention, and portions of the improvements may be used without others.

Having thus described my invention, I claim:

55 1. In a typewriting machine, the combination of a horizontal ribbon-spool at each side

of the machine, instrumentalities for rotating each of said spools to wind the ribbon on either spool, including for each spool a coaxial ratchet-wheel, a drive-pawl, a detent-pawl and a member operatively connected to said drive-pawl and oscillated at each type-blow, devices for disabling the rotating instrumentalities for either spool, including a cam-member coaxial with each spool for controlling the pawls thereof, a connection between said cams, whereby, when the pawls of one spool are made effective, the pawls of the other spool are made ineffective, a normally-ineffective pivoted device operatively connected to each pawl-driving oscillating member to oscillate therewith for operating the associated cam, and mechanism operated by movement of the ribbon when it is substantially unwound from one spool to make the associated pivoted and oscillatable device effective for operating said cams whereby to effect a change in the direction of rotation of said spools.

2. In a ribbon-feed reversing mechanism for a typewriting machine, a ribbon-spool, means for rotating said spool to wind the ribbon thereon, including an upright lever vibrating at each type-blow and an operative connection between said lever and said spool, means for disabling said connection whereby said spool is free to be reversely rotated for feeding said ribbon therefrom, said disabling means including an oscillatable member having an operative connection to said lever and a normally ineffective lever pivoted on said member for movement to effective position, and means actuated by the movement of said ribbon for controlling the operation of said disabling means, said last-named means including a lever-system effective for moving said last-named lever into effective position.

3. The structure described in claim 2 characterized by arranging said oscillatable member for vibration in a plane substantially parallel to said vibratory lever.

4. In a ribbon-feed reversing mechanism for a typewriting machine, a ribbon-spool, means for rotating said spool to wind the ribbon thereon, including an upright lever vibrating at each type-blow, an operative connection between said lever and said spool, means for disabling said connection whereby the spool is free to be reversely rotated for feeding said ribbon therefrom, said disabling means including a rotary cam coaxial with said spool and a thrust-receiving lug depending from said cam, an oscillatable member having operative connection with said lever and a normally-ineffective arm pivoted on the member for movement into effective position to engage with and move said lug, and means actuated by the movement of the ribbon for controlling the operation of said disabling means, the controlling means in-

cluding a lever system effective for moving said arm into effective position.

5. In a typewriting machine of the class described, in combination, a shift-frame having two oppositely-disposed side-plates, a horizontal ribbon-spool supported by each side plate, means for rotating one of said spools ahead for winding up the ribbon thereon, including a ratchet-wheel underlying the ribbon-winding spool and coaxial therewith, a drive-pawl, a detent-pawl, said pawls engaging said ratchet-wheel, devices for releasing said pawls from engagement with said ratchet-wheel, whereby said ribbon-winding spool is free to be rotated in the opposite direction, said device including a rotary plate bearing two cam-edges effective for moving said pawls out of engagement with said ratchet-wheel, said plate being coaxial with said ratchet-wheel and having an extension on the opposite side of its axis from said cam-edges, said extension terminating in close proximity to the adjacent side plate and having two vertical V-shaped notches 25 cut in its outer edge, said adjacent side plate having an aperture disposed adjacent said notches, a ball disposed in said aperture whereby the latter serves as a housing for said ball, and a leaf-spring fastened on the outer face of said adjacent side plate and effective for pressing said ball in against said extension, said aperture and said notches being positioned relative to said cam-edges, so that when the latter are in engagement with 30 said pawls said ball is seated in one of said notches, and when said cam-edges are disposed away from said pawls said ball is seated in the other of said notches.

6. In a device of the class described, having a ribbon-spool, mechanism for rotating said spool and a movable device for disabling said rotating mechanism, the combination of an actuator-carrier member pivoted for movement in a vertical plane transverse to the direction of movement of said device, means for oscillating said carrier, an actuator pivotally mounted on said carrier for engagement with said disabling device, so that the oscillation of said carrier moves said actuator transversely to the direction of movement of the disabling device, and a supporting member fast on said carrier loosely engaging said actuator between its pivot and its outer end, whereby said outer end may 45 operatively engage said disabling devices and effectively transmit power created by the oscillation of said carrier, said supporting member providing lateral movement of said actuator, whereby engagement of the latter with said disabling devices can be controlled independently of said oscillating means.

7. The structure described in claim 6 characterized by an arrangement of the axis of said carrier below the path of the portion of said rotatable disabling device, which is

engaged by said actuator-member, whereby said carrier may be compactly disposed below the ribbon-spool.

8. In a typewriting machine of the class described, in combination, a shift-frame, a ribbon-spool supported on each side of said shift-frame, means for rotating ahead one of said spools at a time, cams for disabling said rotating means, a bracket adjacent each spool on said shift-frame, means for controlling said disabling devices, including a depending piece on each of said cams, a normally-inoperative, oscillating member for engaging said piece, and a lever-system mounted as a unit on said bracket, said lever system being operable by movement of said ribbon for moving said oscillating member to effective position for engaging said depending piece.

9. In a ribbon-feed reversing mechanism of a typewriting machine, in combination, a shift-frame, two horizontally-disposed ribbon-spools on said shift-frame, instrumentalities for rotating each of said spools ahead alternately, devices for disabling said rotating instrumentalities, a controlling unit effective for determining the operation of said disabling devices upon a predetermined movement of the ribbon, said unit including a bracket mounted on said shift-frame, a trip-lever on said bracket movable by said ribbon, a normally ineffective oscillating member on said bracket, an actuator-piece pivoted on said oscillatable member, and a transfer-lever for making the movement of said trip-lever effective to move said actuator-piece to position for engaging said disabling devices.

10. In a typewriting machine of the class described, having a main-frame, a shift-frame and forwardly extending type-bars, the combination of two ribbon-spools, one on each side of said shift-frame, a pawl and ratchet-wheel device for rotating each of said spools ahead, means for automatically reversing the rotation of said spools for feeding the ribbon alternately in opposite directions, said reversing means including a member extending between the sides of said shift-frame and supported thereby below the forward ends of said type-bars, and means effective to raise the pawl of one ratchet-wheel out of operative engagement therewith and concomitantly lower the pawl of the other ratchet-wheel into operative engagement therewith, means for manually reversing the rotation of said ribbon-spools, including a pivoted lever at the front of said machine supported on said main-frame, and an operative connection between said pivoted lever and said member, effective to permit the feed of said ribbon to be manually reversed irrespective of the automatic means for reversing the same, said connection also permitting said automatic reversing means to

function irrespective of the position of said manually-operable reversing lever.

11. In a device of the class described, an actuator-device including a carrier pivoted for oscillatory movement in a front-to-rear vertical plane, a normally ineffective actuator pivoted on said carrier, whereby its free end is movable laterally for engagement with a part to be moved upon subsequent oscillation of said carrier and an integral strap-piece positioned on said carrier between the pivot and the outer end of said actuator, and extending laterally along the outer face of said actuator in the direction of its movement to effective position, said strap-piece guiding said actuator laterally and supporting it against being forced away from said carrier when engaging said part to be moved.

12. In a typewriting machine, the combination with a set of keys, a ribbon-spool rotatably supported on the machine, a pawl-and-ratchet mechanism associated with the spool to feed the ribbon, and a cam for controlling the operation of said feeding mechanism, of a device for setting the cam into effective and ineffective positions, including a pivoted oscillatable element actuated by each stroke of the keys, a lever between the oscillatable element and the keys for rocking the element through a greater angular amplitude than that of the lever, said element moving normally in ineffective positions for movably engaging said cam, and means operable by the movement of said ribbon for moving the element into effective positions for moving the cam to control the ribbon-feed.
